UNITED STATES PATENT OFFICE.

LOUIS WOJIDKOW, OF BROOKLYN, NEW YORK.

DESIGN FOR A CHAFING-DISH.

SPECIFICATION forming part of Design No. 26,431, dated December 22, 1896.

Application filed November 13, 1896. Serial No. 612,036. Term of patent 3½ years.

To all whom it may concern:

Be it known that I, LOUIS WOJIDKOW, a citizen of the United States, residing in Brooklyn, county of Kings, and State of New York, have 5 invented and produced a new and original Design for Chafing-Dishes, of which the following is a specification, reference being had to the accompanying drawing, which shows the same in perspective.

10 The leading feature of my design consists of an outwardly-extending beaded flange, from the base of which rises in compound curves a dome having a circle of beads about the central part thereof and terminating in a 15 knob.

A represents the dish, having the outline, as shown, and handles B.

C represents the top, having the outwardly-extending beaded flange D, from the base of which said top rises in compound curves and 20 is encircled with beads E, said top terminating in the knob F.

What I claim is—

The design for a chafing-dish, as herein shown and described.

LOUIS WOJIDKOW.
